CLAIM

The ornamental design for a lower body garment, as shown and described.

DESCRIPTION

FIG. 1 is a front perspective view of a lower body garment showing my new design with elastic bands located in sleeves extending around the waist and leg openings in an expanded configuration and with cutouts located in the leg portions in place;

FIG. 2 is another front perspective view thereof with the cutouts removed;

FIG. 3 is a rear perspective view thereof with the cutouts in place;

FIG. 4 is another rear perspective view thereof with the cutouts removed;

FIG. 5 is a front elevation view thereof with the cutouts in place;

FIG. 6 is a side view thereof, the opposite side view being identical thereto;

FIG. 7 is a top view thereof;

FIG. 8 is a bottom view thereof;

FIG. 9 is a front elevation view thereof with the cutouts removed;

FIG. 10 is a rear elevation view thereof with the cutouts in place;

FIG. 11 is a rear elevation view thereof with the cutouts removed;

FIG. 12 is a front elevation view thereof with the cutouts removed and with the elastic bands in a gathered configuration; and,

FIG. 13 is a rear perspective view thereof showing one of the cutouts partially removed.

In the drawings the dotted lines are for the purpose of illustrating perforations and form part of the claimed design.
